Primary Examiner—Nelson C. Holtje*Assistant Examiner*—Antoine D. Davis*Attorney, Agent, or Firm*—Keaty & Keaty**[57]****CLAIM**

The ornamental design of a striker attachment for gas cutting torches, as shown and described.

DESCRIPTION

FIG. 1 is a front and left side elevational view of a striker attachment for gas cutting torches showing my new design;

FIG. 2 is a front elevational view;

FIG. 3 is a right side elevational view; and

FIG. 4 is a front and right side perspective view thereof, the broken line showing of a gas cutting torch is environmental only and forms no part of the claimed design.

FIG.1

FIG.2

FIG.3

F I G . 4
